UNITED STATES PATENT OFFICE.

JOHN M. CALDERWOOD, OF SPANISH FORK, UTAH.

DRILL-HOLDER.

1,273,733.

Specification of Letters Patent.

Patented July 23, 1918.

Application filed April 10, 1918. Serial No. 227,758.

To all whom it may concern:

Be it known that I, JOHN M. CALDERWOOD, a citizen of the United States, residing at Spanish Fork, in the county of Utah and State of Utah, have invented certain new and useful Improvements in Drill-Holders, of which the following is a specification.

This invention relates to drill holders.

The present invention has reference to 10 that general class of holders for hand drills such as are used in mining, irrigation, ditch construction, railroad construction, road building, and other work where a hand drill is used which is struck by a sledge or hammer.

My object is to provide, in a holder of the class specified, certain improvements in the standard, the outrigger arm and the drill and hammer supports, whereby adjustability 20 to meet all of the conditions encountered in such work is obtained, whatever the angle at which the drill is to be operated. Furthermore, my invention contemplates the mounting and arrangement of the drill hanger and hammer in such manner that there is no possibility of a misdirected blow but, on the contrary, accurate impact of the hammer or sledge on the drill is obtained, regardless of the angle at which the drill is 30 suspended. With my invention there is no possibility of injury to the hands of the driller who is holding the drill to its work while the hammer operator is operating the hammer or sledge. By the use of the present invention the work of drilling is greatly lightened and two men can about double the work performed in a given time over the time required if the invention were not used.

My invention contemplates a drill holder 40 which can be folded so as to be readily portable, in addition to the novel characteristics of its construction.

One embodiment of the invention is set forth hereinafter and shown in the accompanying drawing. It is to be understood, however, that modifications may be resorted to; furthermore, in several instances where the construction is disclosed as comprising a plurality of parts connected together, it 50 should be understood that they may be made in an integral piece, where adjustability, as between the respective parts, is not required.

In the accompanying drawings:

Figure 1, is a side elevation; Fig. 2, a vertical section, partly broken away;

Fig. 3, a view like Fig. 1, showing the parts adjusted;

Fig. 4, a side elevation, with the parts folded;

Fig. 5, a view on line 5—5, Fig. 1;

Fig. 6, a section on line 6—6, Fig. 1;

Fig. 7, a section on line 7—7, Fig. 5;

Fig. 8, a section on line 8—8, Fig. 1;

Fig. 9, a section on line 9—9, Fig. 2.

The standard 1 may be tubular and is provided with transverse holes 2 at intervals of its height. Secured to its lower end by screw-threads 3 is a cap 4. Telescoped within the standard 1 is a screw-threaded stem 6 which has a squared lower end 7 fixed to a base or foot 8 by a plate 9. A loose nut 10 is carried by the stem 6. An internally screw-threaded adjusting nut 11 is engaged with a screw-threaded stem 6 and interposed between the cap 4 and the nut 10. Loosely mounted on the standard 1 above the cap 4 is a sleeve 12 which is connected by members 13 to the nut 11. Disposed horizontally and entered in an opening 14 in the nut 11 is a lever 15. By swinging the lever 15, the nut 11 will be turned to thereby rotate the latter on the screw-threaded stem 6 and raise or lower the standard. By this means, the base or foot 8 may be pressed against the surface of the ground or a wall after any suitable block has been interposed between the upper end of the standard 1 and an opposing wall, thus firmly anchoring the standard in position so that it cannot move.

Slidable up and down on the standard 1 for positioning at any desired height is a supporting sleeve 16 which has an opening 17 adapted to align with any one of the holes 2. A pin 18 is then passed through the holes to lock the sleeve 16 in position. The sleeve carries a clamping screw 19.

Slidable up and down on the standard 1 is a tubular head 20 whose lower end fits within the upper end of the sleeve 16 so as to be adapted to rotate in relation thereto. The clamping screw 19 is tightened, to lock the tubular head 20 when the latter has been positioned as desired. The tubular head 20 could telescope over instead of within, the sleeve 16.

The drill holder and hammer are supported by an out-rigger arm 21 which may be made in a single piece, or, as a composite construction comprising a wooden center 5 and upper and lower metal plates secured thereto. The arm is hinged to the tubular head 20 at 22 so that it is adapted to fold upwardly along side the standard 1 to condition the parts conveniently for transportation 10 when the device is to be moved from place to place. Projecting downwardly from the arm 21 is a bracket 23 which is adapted to lie against the head 20 and relieve the hinge 22 of considerable strain vertically. 15 The bracket has a yoke 24 which straddles the head 20 and bears against the opposite sides thereof for the purpose of relieving the hinge 22 from lateral strains and, further, to lock the arm 21 rigidly to the head 20. For that purpose, a pin 25 is passed removably through openings 26 in the yoke 24. When the pin is removed the arm 21 can be swung upwardly.

Carried by the arm 21 is a plate 27 having a series of holes 28 to receive a clamping screw 29, used for a purpose which will presently appear.

Embracing and slidable on the arm 21 is a carrier 30 which has parts disposed between the arm and the plate 27, said parts being provided with screw-threaded holes 31 which are adapted to receive the end of the screw 29. According to the position of the carrier 30 on the arm 21, the screw 29 35 will be inserted in a suitable one of the holes 28 to bring it in alignment with one of the holes 31 and will then be entered in the given hole 31 to lock the carrier to the arm 21.

40 The carrier 30 may be of a unitary construction, or, composed of wood with upper and lower plates and metallic straps which embrace the arm 21.

The carrier has a stud 32 on which is pivotally mounted to swing in a vertical plane, 45 the adjusting head 33 which is held against displacement by a nut 34 on stud 32. The head 33 is provided with arc shaped parts 35, of which there may be one or two, each 50 having spaced holes 36. The carrier has screw-threaded holes 37. A bolt 38 is adapted to be entered through any of these holes 36 and screwed into the holes 37 to secure the head 33 in any desired position (Fig. 55 3). A hole 39 in the head 33 and holes 40 in the carrier 30 may also receive the bolt 38 for locking the head 33 in horizontal position (Figs. 1 and 6).

The mountings for the drill support and 60 the hammer or sledge are the same and the following description applies to both.

The head 33 has a squared hole which receives the squared part 41 of a bolt 42, the latter being rigidly fastened by a nut 43. 65 The bolt 42 has a threaded outer end on

which is a nut 44 which retains the hammer or the drill support. The hammer and drill support each have ball or roller bearings 45. Particularly, is this advantageous in connection with the hammer, as it minimizes the effort of the sledge-man in swinging the sledge or hammer.

The drill support has a T-shaped head 46 which carries the ball or roller bearings 45 whereby it may be moved on the bolt 42. 70 To secure the drill carrier at the desired angle, a set screw 47 is used. The shank of the drill support has a joint 48 which enables the drill support 49, with the drill 50 carried thereby, to be swung to one side to position the drill out of line with the hole which has been drilled to enable the drillings to be cleaned out of the hole whenever desired. To lock the parts of the stem in relatively rigid condition, one of said parts 80 is provided with a tongue 51 and the other with a slideable keeper 52 to engage said tongue. On freeing the keeper from the tongue, the stem may be swung on its joint.

The hammer or sledge 53 is of such a 90 length from its point of suspension from bolt 42 that it is adapted to accurately strike the drill 50.

One man, the driller, holds the drill 50 in its support 49 and the other man, the 95 sledge-man, swings the hammer or sledge 53 to and fro to cause it to strike the drill.

With my invention not only can the carrier 30 be moved along the arm 21 to properly position the drill for operation but, in 100 addition, the hammer and the drill support can be tilted up or down to operate the drill at any desired angle. The drill support stem can then be fastened by the set screw 47 so that a straight hole will be 105 drilled. Furthermore, the out-rigger arm and the mechanism carried thereby can be raised or lowered to any desired height on the standard 1 and can then be swung around to position the drill for operation in 110 any part of the field of work. The entire device may be folded into convenient condition for transportation from place to place.

What I claim is:

1. In a drill holder, the combination with 115 a support, of an out-rigger arm carried thereby, a carrier slidable along said arm, an adjusting head pivotally mounted on the carrier, a drill support and hammer respectively pivotally suspended from said adjusting head on opposite sides of the pivotal mounting thereof, means for locking the carrier to the arm, and means for locking the adjusting head to the carrier.

2. In a drill holder, the combination with 120 a support, of an out-rigger arm carried thereby, a carrier slidable along said arm, said arm being provided with apertures at different points of its length, said carrier 125

- having a screw-threaded opening, a screw adapted to be inserted in any one of the openings of the arm and engaged with the screw-threaded opening in said carrier, and 5 a drill support and hammer carried by said carrier.
3. In a drill holder, the combination with a support, of an out-rouge arm carried thereby, a carrier adjustable along the arm 10 and adapted to be secured where adjusted, an adjusting head pivoted to the carrier to swing in a vertical plane and provided with openings located in the arc of a circle struck from the pivotal point of said head, said carrier having a screw-threaded hole adapted 15 to align with the openings in the head, a screw adapted to be inserted through any of the openings and engaged with the screw-threaded hole to lock the head in adjusted
- position, a drill support carried by the head, 20 and a hammer carried by the head.
4. In a drill holder, the combination with a support, of a drill support and a hammer carried thereby, the hammer being adapted for striking a drill carried by said support, 25 said support being adapted for swinging laterally in relation to the hammer to dispose the drill out of line with the hammer.
5. In a drill holder, the combination with a support, of a drill support and a hammer 30 carried thereby, the hammer being adapted for striking a drill carried by said support, said support comprising jointed sections one of which may be shifted laterally in relation to the hammer, and means for locking 35 said sections together in rigid relation.

In testimony whereof I affix my signature.
JOHN M. CALDERWOOD.
